J. W. TURNER

RUBBER HEEL FOR FOOTWEAR

Filed Aug. 21, 1924

Inventor:
Jesseel Webb Turner,

by G. W. H. Evans

Atty.

UNITED STATES PATENT OFFICE.

JESSEE WEBB TURNER, OF BROWNSVILLE, PENNSYLVANIA.

RUBBER HEEL FOR FOOTWEAR.

Application filed August 21, 1924. Serial No. 733,420.

To all whom it may concern:

Be it known that I, JESSEE WEBB TURNER, a citizen of the United States, residing at Brownsville, in the county of Fayette and 5 State of Pennsylvania, have invented a new and useful Improvement in Rubber Heels for Footwear, of which the following is a specification.

The invention relates to rubber heels having a rotatable disk-like tread.

The object of the invention is to provide a simple and effective connection between the rotatable disk-like tread and the fixed portion of the heel.

15 This object I accomplish by the construction shown in the accompanying drawing, in which:

Fig. 1 is a bottom plan view of the heel.

Fig. 2 is a similar view with the rotatable 20 member removed.

Fig. 3 is a transverse section on line 3—3, Fig. 1.

Fig. 4 is a plan of the inner or upper face of the rotatable member.

25 Fig. 5 is a side elevation of the rotatable member.

Fig. 6 is a perspective of a portion of the circular guideway or track on an enlarged scale, and

30 Fig. 7 is a side elevation of one of the guide studs or pins enlarged.

The upper fixed or main portion 1 of the heel will be secured to the heel portion of the shoe, not shown, in any suitable manner.

35 The rubber portion of the heel is formed in two sections 2 and 3 by cutting the rubber on the curved line 4, as shown in Figs. 1 and 2.

A circular track or guideway formed of a 40 metallic ring 5 is embedded and securely fixed in the main portion 1 of the heel and is formed with an under-cut circular groove or channel 6 having its exposed open portion 7 flush with the lower side or bottom 45 of the heel member 1. This channel 6 has a transverse entrance slot or opening 8.

The circular tread or disk 3 is provided with a circularly arranged series of headed pins or studs, shown in detail in Fig. 7, 50 and each comprising a base 10, shank 11 and head 12.

The bases 10 of these pins or studs are 55 embedded in the circular tread or disk 3 with their heads 12 exposed above the upper or inner face of the tread or disk.

The heads 12 are successively entered into

the circular guideway 6 by passing said heads through the entrance opening or slot 8 and turning the tread or disk until all of the studs are in the said guideway; the 60 shanks 11 lying in the open portion 7 and the heads 10 in the under-cut circular groove or channel 6, where they will be securely held and in turn hold the tread or disk 3 firmly against the main portion 1 of the 65 heel.

The tread or disk has a central aperture 14 through which an adjusting screw 15 is passed into the main portion 1, as at 16.

The heel will now appear as in Fig. 1. 70

By loosening the screw 15 the rotatable tread or disk 3 may be turned to bring a different portion thereof to the position occupied by the worn portion, and thus the life of the heel may be greatly prolonged and 75 greater comfort afforded the user.

The portions 2 and 3 of the rubber heel are provided as usual with the raised anti-slipping portions 19.

What I claim is:

1. A heel for footwear comprising a main fixed member, a rotatable disk-like tread, a circular under-cut guideway and a circularly arranged series of headed studs or pins guided in said guideway and said studs 85 and guideway adjustably and rotatably connecting said main and rotatable tread members.

2. A heel for footwear comprising a main fixed member; an annular guideway set 90 flush in the lower face thereof and having an under-cut annular groove open at its lower side, and a disk-like tread having a circular series of headed pins the shanks of which project through the open side of the annular groove and with their heads lying in the under-cut portion thereof.

3. A heel for footwear comprising a main or fixed member, an annular guideway set flush with the lower face thereof and having an under-cut annular groove open at its lower side, a disk-like tread having guide pins or studs extending through the open lower side of the guideway and provided with heads lying in the under-cut portion, and a central adjusting screw extending through the tread into the main portion of the heel. 100

4. A connecting means for rotatable heel treads comprising an annular track adapted to be embedded in the fixed member of a heel and formed with an under-cut groove or channel open at its lower side, and a plu- 110

rality of guide pins or studs having bases adapted to be embedded in a rotary disk-like tread member with their shanks extending through the circular channel opening and their heads within said under-cut groove or channel.

5. A heel for footwear comprising a main or fixed portion, an annular guide set flush in the lower face thereof and formed with
10 an under-cut groove open at its lower side and having a transverse cut-away entrance slot or opening, a rotary disk-like tread

having a series of pins or studs having heads adapted to successively enter the under-cut groove through said transverse cut-away entrance slot and guide the said tread when rotated. ¹⁵

In testimony whereof I affix my signature in the presence of two witnesses.

JESSEE WEBB TURNER.
